Specification of Letters Patent.

Patented Nov. 17, 1914.

Application filed June 18, 1912. Serial No. 703,431.

To all whom it may concern:

Be it known that I, ROBERT F. WARD, a citizen of the United States, residing at Kingstree, in the county of Williamsburg and State of South Carolina, have invented certain new and useful Improvements in Cultivators; and I do hereby declare the following to be a full, clear, and exact description of the invention, such as will enable others skilled in the art to which it app pertains to make and use the same.

This invention relates to straddle row cultivators provided with disks; and it consists in the novel construction and combination 15 of the parts hereinafter fully described and claimed.

In the drawings, Figure 1 is a plan view of a cultivator constructed according to this invention. Fig. 2 is a rear end view of the 20 same with the handles removed. Fig. 3 is a side view of the cultivator.

The draft beam 2 of the cultivator is drawn along in any approved way, and it is provided with handles 3 for guiding it. 25 A crossbeam 3 is secured under the beam 2, and it consists of two parallel plates 4 secured together by rivets 5 and distance pieces 6, so that horizontal openings 7 are formed between the plates. The middle 30 part of the crossbeam 3 is secured to the rear end portion of the draft beam by a vertical bolt 9, and 10 a forked and downwardly and rearwardly curved support or arm for supporting the fender disks 11. 35 The fender disks 11 are journaled on pins 12 at the free end portions of the forked support or arm. The upper end portion of the arm 10 is provided with a longitudinal slot 14 which permits the position of the 40 fender disks to be adjusted.

Spindles 15 are provided and are adjustable horizontally in the openings 7 of the crossbar. The spindles have nuts 16 at their front ends for securing them to the crossbar, 45 and they have brackets 17 pivoted on the rear end portions. These brackets have vertical bearings 18 on one side of their pivots, and curved slots 19 on the other side of their pivots. Notched plates 20 are 50 formed on or secured to the bottom ends of

the bearings 18. Bolts 21 pass through the curved slots 19 and the openings 7 of the crossbar, and these bolts clamp the brackets to the crossbar after the bearings have been adjusted on the pivots. The spindles 15 have shoulders or collars 22 which bear 55 against the edges of the plates of the crossbar.

Forked standards 24 are provided, and they have vertical spindles 25 at their upper 60 parts which are journaled in the bearings 18. The standards 24 are provided with pins or catches 23 of any approved make for engaging with the notches of the plates 20 after the position of the standards has been 65 adjusted.

The cultivator disks 26 are mounted on shafts 27 in the lower parts of the forked standards 24. These disks are set at any desired angles with the vertical and with the 70 line of draft, by turning the brackets on the spindles 15 and by turning the spindles 25 in their bearings. These disks 26 cultivate the ground on each side of the row of plants. The fender disks also cultivate the ground 75 adjacent to the stems of the plants, and they protect the stems from injury.

What I claim is:

The combination, with a cultivator provided with a draft beam, and cultivating 80 devices secured thereto; of a continuous downwardly curved plate of substantially uniform width, said plate having a longitudinal slot in its lower and middle portions, fender disks arranged in the said slot 85 and journaled on pins having spaces between their inner ends and projecting inwardly from the forked lower end portion of the said plate, and means for clamping the upper part of the plate to the beam to 90 support the fender disks at a predetermined height above the bottom portions of the said cultivating devices and permit the slotted plate to clear the growing plants.

In testimony whereof I have affixed my 95 signature in the presence of two witnesses.

R. F. WARD.
